UNITED STATES PATENT OFFICE

MILLER A. MCCREARY, OF DANVILLE, ILLINOIS, ASSIGNOR TO THE HEGELER ZINC COMPANY, OF DANVILLE, ILLINOIS, A CORPORATION OF ILLINOIS

ROLLING MILL INSTALLATION

Application filed April 14, 1930. Serial No. 444,258.

This invention relates to rolling mill installations particularly designed and adapted for rolling or breaking-down slabs of zinc metal to form strips of suitable thickness for coiling, comprising a rolling mill proper, a roller's table adapted for delivering slabs to the rolling mill, a catcher's table adapted to receive the slabs after they have passed through the rolling mill, a return table adapted to receive slabs from the catcher's table and to deliver them at the front or entering side of the rolling mill proper, and a slab wheel adapted to deliver the slabs from the return table to the roller's table to be again passed through the rolling mill, this operation being repeated until the slabs have been broken-down to a desired thickness.

Considered broadly, all of the foregoing features and elements are old and well known and will readily be understood by persons familiar with the art from an inspection of the drawings and without a description thereof in detail.

As is generally well known, the operation of rolling or breaking down zinc slabs into strips of suitable thickness for coiling, is effected by passing it through the rolling mill as many times as may be necessary to reduce it to the thickness desired, this operation, in accordance with the present invention, necessitating the delivery of the slabs after each rolling operation from the delivery to the entering side of the rolling mill, and a primary object of the invention is to provide a rolling mill installation for the purposes specified, designed and adapted for effecting continuous rolling of a plurality of zinc slabs,—a practicable number being up to ten (10)—which are successively passed through the rolling mill in series, in which manual labor in handling the slabs is practically eliminated—excepting for guiding the slabs and controlling their movements—thereby effecting a large saving in labor cost; rendering the work of the operatives more efficient through reduced effort on their part; and also rendering it practicable to operate on much heavier slabs than heretofore, all of which factors have resulted in largely in-

creased capacity and corresponding reduction of production costs, as compared with any other rolling mill installation of which I have any knowledge.

To effect the foregoing object, a rolling mill installation embodying my invention and improvements comprises the various features, combinations of features and details of construction hereinafter described and claimed.

In the accompanying drawings, in which the invention is fully illustrated,

Fig. 1, 1' is a diagrammatic top plan view of a rolling mill installation embodying my invention and improvements.

Fig. 2, 2' is a diagrammatic side view of the installation from the lower side of Fig. 1, 1'.

Fig. 3, 3' is a diagrammatic side view, corresponding substantially to Fig. 2, 2', of the return table for delivering slabs after they have passed through the rolling mill, from the rear to the front side of the rolling mill preliminary to making another pass.

Fig. 4 is a sectional view substantially on the line 4—4 of Fig. 1.

Fig. 5 is a detached perspective view illustrating a stop control mechanism for the slabs as they are returned to the front side of the rolling mill after passing through the same.

Fig. 6 is a detail diagrammatic view on the line 6—6 of Fig. 1'.

Fig. 7 is a similar view on the line 7—7 of Fig. 1'; and

Fig. 8 is a sectional view on the line 8—8 of Fig. 1', illustrating means for imparting step-by-step rotation to the cooling wheel.

For purposes of clear and definite illustration and description, I will assume that my improved rolling mill installation is designed and adapted for rolling or breaking-down slabs substantially 5 ft. long x 10 in. wide x 2 in. thick and which weigh approximately 304 pounds. Obviously, however, the dimensions and weight of the slab admits of wide variation depending upon the kind of strip which is to be produced.

A rolling mill installation embodying my invention and improvements comprises a rolling mill, designated as a whole, A. Rolling

75

80

85

90

95

100

mills suitable for the purpose may be purchased commercially and it is, therefore, unnecessary either to show or describe a rolling mill in detail.

Directly associated with the rolling mill A, one at the entering side and the other at the discharge side thereof, are tables designated, respectively, as a whole, B, B', the table B being adapted to support the slabs in position for delivering them between the rollers of the mill A, and the table B' being positioned to receive slabs from said rolling mill.

In accordance with common practice, the tables B, B' may be variously constructed, for example, they may have smooth sheet-metal tops, either with or without rollers and may be either inclined or horizontal. As shown, the roller's table B is downwardly inclined toward the rolling mill A and the catcher's B' is substantially horizontal, and both of said tables are equipped with idle or anti-friction rolls.

Tables B, B' are old and well known and can readily be furnished by mechanics skilled in the art and it is, therefore, unnecessary either to show or describe said tables in detail.

Having passed through the rolling mill A and been delivered upon the catcher's table B', the slabs are adapted to be returned to the front or entering side of the rolling mill and again passed through the same until reduced or broken down to a desired thickness by suitable means provided for the purpose. As shown, said means are as follows: Positioned at one side of and in spaced relation to the roller's table B and catcher's table B' and extending lengthwise substantially co-expansive therewith, is a return table C upon which the slabs, after each pass through the rolling mill, are adapted to be delivered from the catcher's table B'. As regards its general features, the table C is of substantially the same construction as the roller's and catcher's tables B, B' and can readily be supplied by persons skilled in the art, and need not, therefore, be shown or described in detail.

To provide for delivering slabs from the catcher's table B upon the return table C without lifting them, the top of said return table C is positioned at a lower level than the top of the catcher's table B', and extending from said catcher's table to said return table are inclined skids or slides c, the relation being such that slabs pushed sideways from the catcher's table B' onto said skids or slides will descend along the same by gravity onto the table C, said table being provided with a spring stop c' which projects above the top of the table in position to stop said slabs and to define their position on said return table.

As shown, said spring stop c' consists of a bar 1 supported at the side of the table C

remote from the table B', said bar being supported at the upper ends of bars 2 pivoted to the floor or other supporting surface at their lower ends, and which are held yieldingly in position by rods 3 to which they are secured and which extend beneath the table C and through holes formed in fixed supporting bars 4 secured to the frame of the table C at the side thereof adjacent the table B'. The pivot bars 2 are yieldingly supported by coiled springs 5 inserted between the legs or supports 4 and nuts or other heads 6 on said rods 3.

The table C comprises sections C', C², the section C' being downwardly inclined to the horizontal from its extreme rear end to a point substantially in line with the front side of the housing of the rolling mill A, and the section C² being substantially horizontal, the top surface thereof being only slightly above the floor or supporting surface on which the rolling mill A is erected, and considerably lower than the top surface of the roller's table B.

As shown, the table C is equipped with rollers which, for the most part, are idle, so that slabs delivered upon said table from the catcher's table B' will move along said table impelled by gravity only, or at most, will require very little force to move them endwise thereon. However, at about the lower end of the inclined section C' of said table, there are a number of live rollers c², which, as shown, are adapted to be driven by means of suitable driving connection with a motor c³, consisting, as indicated, of a counter-shaft c⁴, a pulley on which is belt connected with pulleys on the shafts of said rollers c². As shown, said live rollers c² are driven by a single belt adjusted back and forth over pulleys secured to the shafts of said live rollers and intermediate idle rollers c⁵ rotatably mounted on suitable fixed studs, in a familiar manner. To provide for quickly and conveniently starting the rollers c², and for stopping them when desired, the connection between the armature shaft of the motor and the counter-shaft c⁴ is of a usual pulley and belt type. The pulley on the counter-shaft is relatively much larger than that on the armature shaft, in order to obtain a suitable speed reduction, and the pulley on the counter-shaft is adapted to be secured to and disengaged from said shaft by means of a suitable clutch adapted to be thrown in and out of engagement by means of a manually operable lever c⁶.

It is found in practice that when the clutch which drives the counter-shaft c⁴ is thrown out, the inertia of the live rollers c² and their driving connections will effectively brake slabs passing along the section C' of the return table, operating to stop and hold the same until the driving clutch therefor is again thrown in.

Installation of suitable driving means for the live rollers c^2 , together with suitable clutch mechanism can readily be effected by skilled mechanics from the foregoing description without a further description thereof in detail.

The motor c^3 , counter-shaft c^4 and associated mechanism will be mounted below the tops of the skids or slides c positioned in the corresponding portion of the return table C, while the clutch operating lever c^6 , is accessibly mounted at the side of said return table remote from the catcher's table B', where it will not obstruct movement of slabs from said catcher's table to the return table.

Slabs on the section C² of the return table C, which is substantially co-extensive with the roller's table B, are adapted to be delivered from said return table to said roller's table to be again passed through the rolling mill A, by means of what for convenience may be referred to as a slab or cooling wheel, designated as a whole, D, consisting of a shaft d rotatably mounted in suitable bearings formed on pillow blocks or pedestals d' . Secured to rotate with the shaft d are any desired number, as shown eighteen, sets or series of arms d^2 , the arms of each set or series being arranged tangent to circles concentric with the axis of rotation of the shaft d and spaced equal angular distances apart.

With the construction and relation described, in which there are eighteen arms d^2 in each set or series, the outer ends of which are spaced equal distances apart, it is obvious that diametrically opposite arms will be parallel with each other.

In operation, step-by-step rotation through arcs of predetermined length, is adapted to be imparted to the slab wheel D by means presently described, the relation being such that rotation of said cooling wheel in the direction indicated by the arrow, Figs. 6 and 7, will cause the outer ends of the arms d^2 to pass upwardly through spaces d^3 formed between separated portions of the section C² of the return table C, and the relation being such, also, that during periods of rest of said cooling wheel, an arm d^2 of each set or series of arms will extend substantially horizontal and will be positioned in one of the spaces d^3 with its top edge slightly below the top of the section C² of said return table. With this construction, it is obvious that when a slab is supported upon the section C² of the return table in line with the slab wheel C, and rotation is imparted to said slab wheel, the sets of arms d^2 directly beneath said slab will raise the same through whatever arcs are traversed by said arms at each intermittent actuation of said slab wheel.

As shown, there are eighteen arms d^2 in each set or series, and the means for rotating said wheel is constructed and arranged to turn the same through an arc of 20 degrees,

thus rendering it possible for the rolling mill to act in succession on any desired number of slabs, not exceeding ten, and also permitting ample time for the slabs to cool between passes. Between the positions of discharge and "pick-up", the arms will idle.

In the preferable construction shown, the different sets or series of arms d^2 are secured to discs d^4 rigidly secured to the shaft d of said wheel in any suitable manner, as by being bolted, welded, brazed or otherwise secured thereto. Also, to impart desired strength, stiffness and rigidity thereto, said discs are provided at their outer edges with flanges d^5 , which conveniently can be formed by a usual stamping or swedging operation. As shown, also, the arms d^2 are reinforced and strengthened at their inner ends by gusset plates which connect them to the discs to which they are secured, respectively.

Slabs moving along the return table C, between the arms or spokes d^2 of the slab wheel, are adapted to be stopped in different positions after their "following" ends have passed the housing of the roller mill A by suitable stops d^6 provided for the purpose which are adapted to be manipulated manually by an operator. As shown, see particularly Figs. 1', 3' and 5, said stops d^6 are mounted in holes or openings d^7 in the different parts into which the section C² of the return table C is divided by the spaces d^3 , and consist of blocks 8 secured to stub shafts 7 rotatably mounted in flanges formed at the lateral edges of the separate parts of the section C² of the return table C. In operation, rotation is adapted to be imparted to said shafts to cause the free ends of the stop blocks 8 secured thereto to project through the holes or openings d^7 above the top of the return table section C², by means of cam arms 9 secured to said shafts, which project into the path of movement of plates 10 secured to a bar 11 supported so as to be movable endwise and to which endwise movement is adapted to be imparted by means of a manually operable lever 12 which is adapted to be secured in different adjusted positions corresponding to the "setting" of a desired stop block d^6 , by a usual quadrant locking mechanism 13.

At each pass of the slab through the rolling mill A, it will be broken down or reduced in thickness and correspondingly lengthened and the slab or cooling wheel D is made of a length substantially equal to the maximum length of the slabs when rolled or broken down to their final thickness for coiling. Thus, to save unnecessary handling of the slabs as they are delivered from the return table C to the roller's table B, it is desirable that their movement be stopped as soon as practicable after the "following" ends of said slabs have passed the housing of the rolling mill A and, to effect this, a plurality of stops d^6 is provided which become effective

in succession, beginning with the stop closest to the rolling mill and progressively farther therefrom, as the length of the slab increases. In accordance with my invention, I effect this by a construction in which said stops are "set" in succession beginning with the stop which is farthest from the rolling mill and progressively towards the same, until the stop corresponding to any given length of slab is "set".

10 Thus, after the first pass of the slab through the rolling mill, all of the stops will be "set" in succession beginning with the stop farthest from the rolling mill and progressively towards the same, the number of the stops "set" 15 after each pass, being gradually reduced as the slab is broken down and becomes elongated until finally when the slab is fully broken down, only the extreme stop will be "set".

20 To provide for thus "setting" said stop blocks, the plates 10 on the bar 11 which co-operate with the cam arms 9 on the shafts 7 to turn said shafts to raise the free ends of the stop blocks 8, are made of different lengths 25 and are so spaced and positioned that said plates will contact with their corresponding cam arms to set the stop blocks controlled thereby, respectively, at different intervals in the movement of the bar 11, the lengths of 30 said plates 10, respectively, being such, also, that when the bar 11 is moved to effect engagement of any cam arm 9 with its operating plate 10, said cam arm will remain in engagement with said plate throughout the entire contemplated movement of said operating bar to set all of said stops.

Also, with the construction described, when all of said stops have been thus set, they may be released so as to permit their return to 40 inoperative position, by endwise movement of the bar 11 in a reverse direction from its movement to set said stops, said stops also being released progressively in succession beginning with the stop nearest the rolling mill.

45 As step-by-step rotation is imparted to the slab or cooling wheel D, in operation, it is obvious that when the arms on which slabs are supported pass their vertical position, slabs supported thereby will turn by gravity so 50 that they will rest on the arms d^2 adjacent to and in front of arms or spokes on which said slab was initially supported and will continue to rest upon and be supported by said arms until such time as said arms again 55 pass horizontal position at the top side of the wheel and become downwardly inclined at such an angle that the slabs will slide off from the same by gravity. With this relation, it is obvious that by properly positioning the 60 slab or cooling wheel relative to the roller's table B, slabs discharged by gravity from said wheel will be delivered from the slab or cooling wheel D onto the roller's table B from being thrown off from the same, said 65 roller's table preferably will be provided

with spring stops or buffers which may be substantially similar in construction and operation to those applied to the return table C to prevent slabs delivered from the catcher's table B' onto said return table from being thrown off from said return table.

70 In accordance with my invention, step-by-step rotation is adapted to be imparted to the slab or cooling wheel D by means as follows:—

75 Secured to the shaft d of said slab or cooling wheel D so as to rotate therewith, is a ratchet wheel 14 formed on opposite sides of which are bearings fitted to which, respectively, so as to turn freely thereon are rings 15, 15', which may be made of boiler plate or the like, both of which are pivotally connected, respectively, by links 16, 16' with a common pivot pin 17 secured in a pivoted lever 18.

80 The rings 15, 15' are each shaped to form projecting portions or lugs to which, respectively, the links 16, 16' are pivoted, said links being positioned on opposite sides of a vertical line through the center of the ratchet wheel 14, and are proportioned so that they will project beyond the periphery of the teeth of the ratchet wheel 14. Pivotally mounted upon the pivot pins which connect the links 16, 16' to the rings 15, 15', respectively, in position to engage the teeth of the ratchet wheel 14 are pawls 19, 19', the relation being such that upward movement of the free end of the lever 18 will operate to advance the pawl 19' causing it to engage a tooth of the ratchet wheel 14 and thereby 85 impart rotation to said ratchet wheel, and thus to the shaft d of the cooling wheel, and to simultaneously retract the pawl 19, while depression of the free end of the lever 18 will, in like manner, operate to advance the pawl 19 and to retract the pawl 19' into position to engage the next succeeding tooth of the ratchet wheel, both pawls 19, 19' operating 90 upon the pivot pins which connect the links 16, 16' to the rings 15, 15', respectively, in position to engage the teeth of the ratchet wheel 14.

95 100

105 As installed for use, pivotal movement is adapted to be imparted to the lever 18 by means of a cylinder and piston motor 20, opposite ends of the cylinder of which are connected with a suitable source of supply of fluid under pressure by a supply pipe 21 and branch pipes 22 and 23, communication of the pipe 21 and branch pipes 22 and 23 being controlled by a manually operated three-way valve indicated at 24. As shown, the valve 24 is adapted to be operated by means of a hand lever 25 accessibly located adjacent to the roller's table B.

110 115 120 125 130

As shown, the ratchet wheel 14 has nine teeth and the pawl actuating mechanism is so proportioned that at each full stroke of the piston of the motor 20, one of the pawls 19, 19', will be advanced and the other pawl retracted through an arc equal to one-half

of the pitch of the ratchet wheel which, with the relation shown, will be as near as may be 20 degrees, which corresponds with the spacing of the free ends of the arms d^2 of the slab or cooling wheel D under the conditions assumed and heretofore described.

To provide for adjusting the throw of the pawls 19, 19', the lever 18 is provided at its pivoted end with a series of holes 26, arranged at different distances from the pivot pin 17, in which said pivot pin is interchangeable. Thus, by shifting the pivot pin from one of the holes 26 to another, it is obvious that the throw of the pawls may be varied within considerable limits, to meet operating conditions.

To economize space and also to impart desired fall or pitch to the skids or slides c so that slabs will descend the same by gravity from the catcher's table B' onto the return table C, said return table is installed at an angle to the roller's table B and catcher's table B', diverging from the end of the catcher's table remote from the rolling mill A towards the slab or cooling wheel D, which, as shown, is tapered to conform to the divergence of the return table C and the inclination of the roller's table B. Divergence of the return table C relative to the roller's table B and catcher's table B' is rendered necessary in order to provide a slab or cooling wheel D of proper size to raise the slabs from said return table C and deliver them onto the inclined roller's table B.

Obviously, however, to meet different relative conditions of installation, the slab or cooling wheel D may be straight or tapered, horizontal, or inclined, to receive from a return table horizontal or inclined, and to deliver to a roller's table, horizontal or inclined, in any combination.

In accordance with usual practice, the catcher's table B' comprises a pivoted section b which may be raised to provide a space in said catcher's table B' for a portable coiling machine, indicated as a whole, E.

By "zinc" slabs as used in the foregoing specification and within the scope and contemplation of my invention, it is my intention to include zinc alloys which contain sufficient quantities of zinc so that they retain the essential physical characteristics of zinc.

I claim:

1. In a rolling mill installation of the type specified, the combination of a roller's table, a catcher's table, a return table spaced laterally from and positioned below said roller's and catcher's tables, and power actuated transfer means for removing slabs from said return table and automatically discharging them upon the roller's table.

2. A rolling mill installation as specified in claim 1, in which the return table is arranged below both the roller's and catcher's

tables, and declines towards the front end of the installation.

3. A rolling mill installation as specified in claim 1, in which the power actuated transfer means is manually controlled.

4. A rolling mill installation as specified in claim 1, in which the power actuated transfer means comprises a rotatable member and means for imparting step-by-step rotation thereto.

5. In a rolling mill installation of the type specified, the combination of a roller's table, a return table, a slab wheel positioned between said return table and the roller's table, comprising a shaft, spaced series of arms secured to said shaft, each series comprising the same number of arms all of which are tangent to a circle concentric with the axis of said shaft, said return table being provided with spaced openings positioned and proportioned to permit different series of arms to pass therethrough, respectively, and means applied to said shaft for imparting step-by-step rotation to said slab wheel, the roller's table and the shaft of the slab wheel being positioned above the section of the return table in transverse alignment therewith.

6. A rolling mill installation as specified in claim 5, in which the means for imparting step-by-step rotation to the slab wheel also comprises manually operable control means.

7. A rolling mill installation as specified in claim 5, which also comprises a catcher's table positioned above the section of the return table in transverse alignment therewith and which comprises downwardly inclined skids from said catcher's table to said return table.

8. A rolling mill installation as specified in claim 5, which also comprises a catcher's table positioned above the section of the return table in transverse alignment therewith and said section of said return table is downwardly inclined towards the slab wheel.

9. A rolling mill installation as specified in claim 5, which also comprises a catcher's table positioned above the section of the return table in transverse alignment therewith, and said section of said return table is downwardly inclined towards the slab wheel, said installation also comprising downwardly inclined skids from said catcher's table to said return table.

10. A rolling mill installation as specified in claim 5, in which the arms are so arranged that in positions of rest of the slab wheel, an arm of each series will extend substantially horizontal and will be positioned only slightly below the top of the return table.

11. A rolling mill installation as specified in claim 5, in which there is an even number of arms in each series of slab supporting arms and the relation is such that in positions of rest of the slab wheel an arm of each series

130

will extend substantially horizontal and will be only slightly below the top of the return table.

12. A rolling mill installation as specified in claim 5, in which the slab wheel is so proportioned and positioned that as the arms thereof come into substantially horizontal position after passing over the top of the wheel, an arm of each series in front of said horizontal arm will be inclined downwardly at such an angle that a slab supported thereon will be delivered onto the roller's table by gravity.

13. A rolling mill installation as specified in claim 5, in which the slab wheel is so proportioned and positioned that the arms of one series come to rest finally at such an angle of inclination that a slab supported thereon will be delivered onto the roller's table by gravity.

14. A rolling mill installation as specified in claim 5, in which discs are secured to the slab wheel shaft to which, respectively, different series of arms are secured.

15. A rolling mill installation as specified in claim 5, in which marginally flanged discs are secured to the shaft of the slab wheel to which, respectively, different series of arms are secured.

16. A rolling mill installation as specified in claim 5, in which the roller's table is downwardly inclined towards the rolling mill and the slab wheel is tapered and is installed with its large end remote from the rolling mill and its shaft diverging upwardly relative to the horizontal and laterally relative to the catcher's table in a direction away from the rolling mill, and the return table also diverging from the roller's and catcher's tables.

17. A rolling mill installation as specified in claim 5, which also comprises a stop mechanism consisting of a series of movably supported stops adapted, respectively, to arrest movement of slabs along the return table when their "following" ends attain positions in which they will clear the rolling mill, and means for setting said stops.

18. A rolling mill installation as specified in claim 5, which also comprises a stop mechanism consisting of a series of movably supported stops adapted, respectively, to arrest movement of slabs along said return table when their "following" ends attain positions in which they will clear the rolling mill, and means for setting said stops in succession beginning with the stop remote from the rolling mill.

19. A rolling mill installation as specified in claim 5, which also comprises a stop mechanism consisting of a series of movably supported stops adapted, respectively, to arrest movement of slabs along said return table when their "following" ends attain posi-

tions in which they will clear the rolling mill, and manually operable means for setting said stops in succession.

20. A rolling mill installation as specified in claim 5, which also comprises a stop mechanism consisting of a series of movably supported stops adapted, respectively, to arrest movement of slabs along said return table when their "following" ends attain positions in which they will clear the rolling mill, consisting of shafts rotatably mounted at the under side of the return table, stop blocks secured to said shafts, respectively, the relation being such that turning movement of said shafts will cause parts of said stop blocks to project above the return table, a manually operable lever and connection between said lever and stop shafts for turning said stop shafts pivotally.

21. A rolling mill installation as specified in claim 5, which also comprises a stop mechanism consisting of a series of movably supported stops adapted, respectively, to arrest movement of slabs along said return table when their "following" ends attain positions in which they will clear the rolling mill, consisting of shafts rotatably mounted at the under side of the return table, cam arms secured to said stop shafts, a bar mounted so as to be movable endwise, cam plates secured thereto adapted, respectively, to engage the cam arms on said shafts, and an operating lever connected to said bar.

22. A rolling mill installation as specified in claim 5, which also comprises a stop mechanism consisting of a series of movably supported stops adapted, respectively, to arrest movement of slabs along said return table when their "following" ends attain positions in which they will clear the rolling mill, consisting of shafts rotatably mounted at the under side of the return table, cam arms secured to said stop shafts, a bar mounted so as to be movable endwise, cam plates secured thereto adapted, respectively, to engage the cam arms on said shafts, and an operating lever connected to said bar, said cam plates being proportioned, respectively, to maintain all set stops in set position during the full setting stroke of the set lever.

23. A rolling mill installation as specified in claim 5, which also comprises a stop mechanism consisting of a series of movably supported stops adapted, respectively, to arrest movement of slabs along said return table when their "following" ends attain positions in which they will clear the rolling mill, consisting of shafts rotatably mounted at the under side of the return table, cam arms secured to said stop shafts, a bar mounted so as to be movable endwise, cam plates secured thereto adapted, respectively, to engage the cam arms on said shafts, and an operating lever connected to said bar, said cam plates being proportioned, respectively, to maintain

all set stops in set position during the full setting stroke of the set lever, and the relation being such that said stop blocks will fall by gravity to inoperative position when their respective cam arms pass out of engagement with their respective cam plates upon reverse movement of the set lever.

24. A rolling mill installation as specified in claim 5, in which the return table comprises a clutch-driven live roller and means rendered operative by throwing out said clutch for braking said roller to stop movement of a slab resting thereon.

25. A rolling mill installation as specified in claim 5, in which the return table comprises a clutch-driven live roller, the inertia of said roller when the clutch is thrown out operating as a brake to arrest movement of a slab resting thereon.

26. A slab wheel for the purpose specified, consisting of a shaft, spaced series of arms secured thereto, each series comprising the same number of arms all of which are tangent to a circle concentric with the axis of the shaft.

In witness that I claim the foregoing as my invention, I affix my signature this tenth day of April, 1930.

MILLER A. McCREARY.
